ABSTRACT OF THE DISCLOSURE

The invention is embodied in a cold header assembly of the type having a die block assembly and a ram-mounted punch assembly mounted on a composite frame. The composite frame is composed of laterally spaced, separate, elongated side rails connected together by tie bars and held in predetermined spaced relation by spacers sleeved on the tie bars. A bolster plate extends between and is carried by the side rails and supports the die block assembly, and a crankshaft is journaled on the side rails to reciprocate the ram assembly.

SUMMARY OF THE INVENTION

Conventional frames for cold headers have been extremely difficult to manufacture by the use of standard machine tools because of their size and construction. The primary object of this invention is to provide an improved frame of a novel construction for a cold header which can be readily manufactured by the use of standard machine tools and yet which is rigid and sturdy and well suited to carry out its intended function.

Another object of the invention is to provide a composite frame for a cold header composed of separate elongated laterally spaced side rails secured together to form a solid unit.

Another object is to provide a composite frame for a cold header having means for securing the side rails together including tie bars extending across the space between the side rails and having spacers on the tie bars whose opposite ends abut the adjacent surfaces of the side rails.

Another object is to provide a composite frame having a separate bolster plate.

Other objects and features of the invention will become apparent as the description proceeds, especially when taken in conjunction with the accompanying drawings, wherein:

FIG. 1 is a top plan view of a cold header embodying our invention.

FIG. 2 is a sectional view taken on the line 2—2 of FIG. 1.

FIG. 3 is a sectional view taken on the line 3—3 of FIG. 2.

Referring now more particularly to the drawings, the cold header comprises a composite frame 12, a die block assembly 14, a punch assembly 16 and a ram assembly 18.

The composite frame 12 includes a pair of laterally spaced, substantially parallel, separate, elongated side rails 20 and 22 which in the present instance are supported in horizontal position on any suitable base or support structure. The side rails have laterally inwardly extending front end portions 23 which terminate in spaced relation to one another. The side rails are connected together by transverse horizontal tie bars 24, 26 and 28.

The tie bar 24 adjacent the front end of the side rails is disposed at right angles to the side rails and to vertical surfaces 38 and 40 and extends through passages in the front end portions 23. The opposite ends of tie bars 24 extend into recesses 30 and 32 in the outer or remote side surfaces of the side rails. Nuts 34 in the recesses 30 and

2

32 are threaded on the opposite ends of the tie bar 24. A tubular spacer 36 is sleeved on the tie bar 24 and its ends abut the opposed surfaces 38 and 40 of the side rails. The tie bar assembly including the tie bars 24, nuts 34 and spacer 36 rigidly connect the side rails 20 and 22 together in predetermined spaced relationship at the front end thereof.

The tie bars 26 and 28 are located adjacent the rear end of the composite frame and extend through passages in the side rails at right angles to the side rails and to the vertical inner surfaces 46 and 48 thereof and to the stepped back vertical surfaces 47 and 49. The opposite ends of the tie bars 26 and 28 extend beyond the outer or remote side surfaces of the side rails, and nuts 42 are threaded on the ends of the tie bars 26 and 28. Tubular spacers 44 and 45 are respectively sleeved on the tie bars 26 and 28 in the space between the side rails. The opposite ends of the spacer 44 abut the opposed surfaces 47 and 49 of the side rails and the opposite ends of the spacer 45 abut the opposed surfaces 46 and 48. The tie bar assemblies including tie bars 26 and 28, nuts 42 and spacers 44 and 45 rigidly connect the rear end portions of the side rails together in predetermined spaced relationship.

25 A rectangular bolster plate 54 extends between the side rails 20 and 22 adjacent the front end of the composite frame 12. As seen in FIG. 1, the front end portions 23 have opposed, generally U-shaped vertically extending grooves 56 and 58 located just rearwardly of surfaces 38 and 40. The opposite vertical edge portions of the bolster plate 54 are received in the grooves 56 and 58. The grooves are open at the upper ends so that the bolster plate may be installed by being lowered vertically into position. The bolster plate provides a support for the die block assembly 14.

30 As seen in FIGS. 2 and 3, the bolster plate 54 is located in fixed position by bolster keys 60 and 62 which fit into registering grooves or slots 64 and 66 in the opposed surfaces of the side rails and bolster plate. The bolster plate 54 is secured in this position by studs 70 extending through the side rails and threaded into the bolster plate. The studs have nuts 72 on their outer ends, and recesses 73 in the side rails accommodate the outer ends of the studs and the nuts.

35 Just to the rear of the slots 56 and 58, the front end portions 23 of the side rails have vertical but tapering opposed surfaces 78 and 80 which provide a dovetail slot for the die block assembly 14. The slot is open at the upper end and the die block assembly has side surfaces tapering to correspond with the surfaces 78 and 80 of the slot so that the die block assembly may be installed by being lowered vertically into position. The upper rear edge of the bolster plate has a recess providing a horizontal ledge 84 extending across the width thereof, and the front upper edge of the die block assembly has an extension or lip 86 which is received in and rests upon the ledge 84 to vertically locate the die block assembly and prevent it from descending below the position shown in FIG. 2. A wedge 85 or any other suitable means may be provided for locking the die block assembly in position.

40 The ram assembly 18 is reciprocable lengthwise of the composite frame 12 and has longitudinally extending horizontal grooves 90 in its opposite sides. Grooves 90 receive elongated horizontal gibs 92 on the side rails to guide the reciprocation of the ram. The front end surface of the ram assembly 18 has a vertical dovetailed slot 94 in which is received a dovetailed mounting portion 96 of the punch assembly 16. The slot 94 is open at the upper end so that the punch assembly 16 may be installed by lowering it into position. Any suitable means may be

provided for locating and locking the punch assembly in the position shown in FIG. 2, such for example as an adjusting screw with or without a wedge.

The punch assembly 16 has a punch 98 opposed to the die block assembly 14 for upsetting a metal slug upon forward movement of the ram assembly 18 toward the die block assembly 14.

A crankshaft 99 extends transversely between the side rails 20 and 22 and is journaled in bearings 100 in the rear end portions of the side rails. The eccentric central portion 102 of the crankshaft between the side rails has a crank bushing 104 on which a pitman 106 is journaled, and the pitman has a pitman roll 108 journaled on a pivot pin 110 carried by the ram assembly 18 so that rotation of the crankshaft 99 operates through the pitman 106 to reciprocate the ram assembly 18. The ram assembly is shown in FIGS. 1 and 2 at the forward end of its stroke. Raised pads 111 on the side rails 20 and 22 center the pitman 106.

Power to drive the crankshaft 99 is received from a source, not shown, through belting 112 trained over the flywheel 114 connected to one end of the crankshaft 99.

What we claim as our invention is:

1. In a cold header assembly of the type having a die block assembly and a ram-mounted punch assembly cooperable with one another to upset a workpiece, a composite frame including laterally spaced, substantially parallel, separate, elongated side rails adapted to extend along opposite sides of and support said assemblies, and means for securing said side rails in the aforesaid laterally spaced relation including tie bars extending across the space between said side rails, said tie bars having abutment means between said side rails engaging the adjacent opposed surfaces of said side rails, said abutment means comprising spacers sleeved on said tie bars, the ends of said spacers abutting the adjacent opposed surfaces of said side rails.

2. In a cold header assembly of the type having a die block assembly and a ram-mounted punch assembly cooperable with one another to upset a workpiece, a composite frame including laterally spaced, substantially parallel, separate, horizontal elongated side rails adapted to extend along opposite sides of and support said assemblies, said side rails having laterally inwardly extending portions at the front ends thereof terminating in spaced relation to one another, vertical opposed grooves in the confronting surfaces of said laterally inwardly extending portions which are open at the top, a bolster plate extending across the space between said side rails having opposite edge portions insertable into said grooves from the top and secured therein to provide a support for said die block assembly, and means for securing said rails in the aforesaid laterally spaced relation including a tie bar extending between said rails across the space separating said laterally inwardly extending portions forwardly of said bolster plate, a spacer sleeved on said tie bar between said side rails and having its ends abutting the confronting surfaces of said laterally inwardly extending portions, at least one tie bar adjacent the rear ends of said side rails extending across the space between said side rails, and a spacer sleeved on the second-mentioned tie bar between said side rails having its ends abutting the adjacent opposed surfaces of said side rails.

3. The structure defined in claim 2, wherein said side rails have recesses in their laterally outer surfaces into which the opposite ends of one of said tie bars extend, and nuts in said recesses threaded on the ends of the said one of said tie bars.

4. The structure defined in claim 2, wherein said laterally inwardly extending portions have vertical opposed, dovetailed surfaces rearwardly of said grooves which are open at the top for the downward insertion of the die block assembly.

5. The structure defined in claim 2, wherein said side rails have horizontal guide means for guiding the movement of a ram for carrying the punch assembly.

15 6. The structure defined in claim 5, wherein said side rails have journals near their rear ends for a crankshaft to reciprocate the ram.

7. The structure defined in claim 2, wherein said bolster plate has a ledge for vertically locating the die block assembly.

20 8. In a cold header assembly of the type having a die block assembly and a ram-mounted punch assembly cooperable with one another to upset a workpiece, a composite frame including laterally spaced, substantially parallel, separate, elongated side rails adapted to extend along opposite sides of and support said assemblies, and means for securing said side rails in the aforesaid laterally spaced relation including a tie bar extending across the space between said side rails, means on said tie bar opposing movement of said side rails away from one another, and means on said tie bar opposing movement of said side rails toward one another, said last-mentioned means comprising a spacer sleeved on said tie bar in the space between said side rails, said side rails have opposed grooves in adjacent surfaces which are open at one end, and a bolster plate extending across the space between said side rails having opposite edge portions insertable into said grooves through the open ends thereof and secured therein to support the die block assembly.

25 9. In a cold header assembly of the type having a die block assembly and a ram-mounted punch assembly cooperable with one another to upset a workpiece, a composite frame including laterally spaced, substantially parallel, separate, elongated side rails adapted to extend along opposite sides of and support said assemblies, and means for securing said side rails in the aforesaid laterally spaced relation including tie bars extending across the space between said side rails, said tie bars having abutment means between said side rails engaging the adjacent opposed surfaces of said side rails, said abutment means comprising spacers sleeved on said tie bars.

30 40 10. In a cold header assembly of the type having a die block assembly and a ram-mounted punch assembly cooperable with one another to upset a workpiece, a composite frame including laterally spaced, substantially parallel, separate, horizontal elongated side rails adapted to extend along opposite sides of and support said assemblies, and means for securing said side rails in the aforesaid laterally spaced relation including tie bars extending across the space between said side rails, said tie bars having abutment means between said side rails engaging the adjacent opposed surfaces of said side rails, said abutment means comprising spacers sleeved on said tie bars.
